UNITED STATES PATENT OFFICE.

JOHAN WALDEMAR LINDBERG, OF STOCKHOLM, SWEDEN.

SELF-LOCKING DOOR-LOCK.

1,244,872.

Specification of Letters Patent. Patented Oct. 30, 1917.

Application filed May 18, 1917. Serial No. 169,496.

To all whom it may concern:

Be it known that I, JOHAN WALDEMAR LINDBERG, a subject of the King of Sweden, residing at Stockholm, in the Kingdom of

5 Sweden, have invented a new and useful Improvement in Self-Locking Door-Locks, of which the following is a specification.

This invention relates to an improvement in such door-locks in which the latch-bolt is 10 beveled off so that when closing the door, it becomes pushed into the lock casing owing to the pressure on the beveled surface, again to snap into locking position when the door has assumed its closed position. In 15 order that the closing may be effected in the said manner, the bolt must be in such position preparatory to the closing of the door that only the bevel projects beyond the face plate of the lock. In locks of this kind here- 20 tofore in use, the latch bolt must be brought to this intermediate position by means of a key or in some other manner before shutting the door, but this may easily be forgotten, or the adjustment may be incomplete or incor- 25 rectly done on account of defects in the mechanism of the lock. Efforts have also been made to design locks where this adjustment of the bolt is effected automatically when opening the lock, but the arrangements 30 have become far too complicated and thus unreliable in working, particularly in so far as the bolt, even if it has been brought into its intermediate position, may still fail to return to its final locking position. The 35 present invention has for its purpose to avoid these drawbacks. The invention is principally characterized by this, that the bolt-actuating member is provided with a projection or the like coacting with a hook 40 or the like on the latch bolt, or with some part connected with the same, in such manner that when the bolt-actuating member has retracted the bolt entirely in order to open the lock, and both of them return outward 45 to locking position (actuated by springs), the projection on the bolt-actuating member will engage the hook on the bolt in such manner that this latter is retained in the intermediate position in which its beveled sur- 50 face is in such position as to be acted upon for pushing back the bolt when the door is being closed.

In the accompanying drawing the interior of a door-lock arranged according to the 55 present invention, is shown by way of example. Figure 1 shows the locking position,

Fig. 2 the unlocked position, Fig. 3 the intermediate position adjusted for shutting the door, and Fig. 4 the latch bolt locked in open position.

60

The latch bolt 1 is connected with a plate 2 the front edge 3 of which bears against the head of the bolt and the rear end of which is provided with a shoulder 4 at right angles to the bolt, the latter shoulder being formed 65 into a hook 5 at its upper end. The bolt is made so that it may be turned and used either for right-hand or for left-hand locks in known manner, and the turning of the latch bolt is effected simply by loosening the bolt from the plate 2, the shoulder 4 and the hook 5 of which remain in unchanged position. In the lock casing above the latch bolt 70 there is fulcrumed a lever 6 (the securing hook) the hooked end 7 of which may coact 75 with a projection 3¹ on the plate 2 so as to lock the bolt in its end positions. The said lever is also provided with a lug 8 which projects into the path of the upper end 10 of the bolt-actuating member 9 so that the lever 6 80 may be actuated by the member 9, in order to release the bolt. The bolt-actuating member is also provided with a projection or a lug 11 which presses against the shoulder 4 of the plate 2, when the bolt-actuating member 85 is turned, and moves the bolt from locking position rearward to open position. A spring 19 is illustrated at 19 and is preferably coiled around and anchored to a suitable stud 20, one end of said spring bearing against the 90 inner end of the bolt 1 and acting to urge said bolt outwardly, while the other end thereof bears upwardly against the shoulder 9' formed on the bolt-actuating member 9 and is adapted to rock said bolt-actuating 95 member 9 in one direction. It will therefore be noted that said spring 19 is common to both the bolt and the bolt-actuating member and acts to operate both. (Fig. 2). When the bolt moves outward toward the 100 locking position actuated by the spring 19, the lug 11 slides upward along the shoulder 4 until it engages the hook 5 formed at the end of the said shoulder. The latch bolt is then in an intermediate position (Fig. 3) in 105 which its beveled portion only projects outside the lock casing. In locking position the bolt projects so far out that a plane portion (parallel with the direction of movement of the bolt) will also reach outside the lock cas- 110 ing (Fig. 1). The bolt-actuating member has a projecting arm 12 close to the hub, and

located in the path of a lever 13 which may be operated by the key 14. Besides, the lock is provided with tumblers 15, and the moving parts are in known manner actuated by 5 means of springs.

When the bolt assumes its extreme protracted or locking position, it is locked by the front end of the lever 6 bearing against the projection 3¹ on the plate 2 (Fig. 1). 10 When the key is turned for opening the lock, it presses against the lever 13 which then acts upon the bolt-actuating member 9 so that this latter lifts the lever 6 and releases the bolt. On continued turning of the 15 bolt-actuating member 9, the lug 11 of the same forces the bolt rearward to open position (Fig. 2). When the key is then released, the bolt is driven outward by the spring 19 and brings along the bolt-actuating member, the lug 11 of which then slides along the shoulder 4 until it engages the hook 5, when the further outward movement of the bolt is prevented. The bolt now assumes the above-mentioned intermediate 20 position (Fig. 3) in which its beveled portion only projects on the outside of the lock casing, and its oblique surface is then in such a position that it may be acted upon for pushing the bolt rearward when shutting 25 the door. At this movement of the bolt the bolt-actuating member is also brought rearward until it arrives so far that its lug 11 releases the hook 5, when it moves forward under the action of the spring 19 until the 30 arm 12 of the bolt-actuating member 9 strikes against the lever 13. At the same time the bolt is also pushed forward under the action of said spring 19 and assumes the final locking position shown in Fig. 1. By 35 this arrangement it is thus always guaranteed that when the door is being shut, the position of the latch bolt is such that the bolt may be forced rearward. If the door is to stand unlocked, the bolt is drawn back 40 by turning the key 14 or a handle (not shown) secured to the bolt-actuating member 9, to the position shown in Fig. 2, and before releasing the key or the handle the bolt is pushed farther in by hand until the 45 hooked end 7 of the lever 6 falls down before the projection 3¹ of the plate 2 (Fig. 4) and maintains the bolt in its pushed-in position. At this pushing in of the latch bolt a lug 18 on the plate 2 serves to stop the 50 forward movement of the bolt-actuating member, when the key or the handle is released, so that the outer end 10 of the said member must stay behind the lug 8 on the lever 6 as shown in Fig. 4. When the door 55 is again to be locked, the bolt-actuating member is moved so that the lever 6 is lifted and the bolt is released and pushed by its spring into locking position. The last men-

tioned movement of the bolt-actuating member must take place forward, that is to say, 65 to the left in Fig. 1, on account of the bolt-actuating member having been moved behind the lug 8 by the lug 18 at the pushing in of the bolt, and the bolt-actuating member is thus prevented from entering the 70 notch 5 and stopping the bolt in its intermediate position which might happen if the bolt-actuating member were instead to be moved to the right.

It is obvious that various changes and 75 modifications may be made in the detailed construction herein illustrated and described and the right is therefore reserved to make such changes and modifications as fall within the scope of the appended claims. 80

I claim:

1. A door lock of the type described comprising a beveled bolt, a hook connected to said bolt, a bolt-actuating member, a lug on said bolt-actuating member, resilient means 85 common to said bolt and to said bolt-actuating member adapted to effect an engagement between said lug and said hook when said bolt has been retracted to a position intermediate its maximum retracted and maximum extended positions to thereby retain said bolt in such intermediate position, and means whereby said bolt is automatically locked in its maximum extended position 90 when the door is closed. 95

2. A door lock of the type described comprising a beveled bolt, a plate connected to said bolt, a shoulder at the inner end of said plate, a hook at the top of said shoulder, a bolt-actuating member, and a lug on said bolt-actuating member adapted to slide against said shoulder and to engage said hook to thereby retain said bolt in a position intermediate its maximum retracted position and its maximum extended position, thereby affording means whereby said bolt may be actuated by the engagement of the beveled portion thereof with the jamb escutcheon when the door is being closed. 100 105

3. A door lock of the type described comprising a bolt, a shoulder on said bolt, a hook on said shoulder, a lever adapted to lock said bolt in its maximum retracted position and in its maximum extended position, a bolt-actuating member co-operating 110 with said lever and with said shoulder to disengage said lever and to retract said bolt and means on said bolt-actuating member adapted to engage said hook when said bolt has been retracted to a position intermediate 115 its maximum retracted and maximum extended positions and to retain said bolt in such intermediate position. 120

4. A door lock of the type described comprising a bolt, a shoulder on said bolt, a hook on said shoulder, a lever adapted to 125

lock said bolt in its maximum retracted position and in its maximum extended position, a bolt-actuating member coöperating with said lever and with said shoulder to disengage said lever and to retract said bolt, and means on said bolt-actuating member adapted to engage said hook when said bolt

has been retracted to a position intermediate its maximum retracted and maximum extended positions and to retain said bolt in such intermediate position, said bolt being automatically locked in its maximum extended position when the door is closed.

JOHAN WALDEMAR LINDBERG.
